Patented Mar. 17, 1914.

FIG. 3.

FIG. 1.

FIG. 2.

UNITED STATES PATENT OFFICE.

HERBERT G. DE HAMEL, OF ALDBURY, TRING, ENGLAND, AND GEORGE MAKGILL, OF KEMBACK, SCOTLAND.

ADVERTISING SIGN OR DEVICE.

1,090,707.

Specification of Letters Patent. Patented Mar. 17, 1914.

Application filed January 4, 1913. Serial No. 740,215.

To all whom it may concern:

Be it known that we, HERBERT GUSTAVE DE HAMEL and GEORGE MAKGILL, subjects of the King of Great Britain, residing at The 5 Yews, Aldbury, Tring, Hertfordshire, England, and Kemback, in the county of Fife, Scotland, respectively, have invented certain new and useful Improvements in Advertising Signs or Devices, of which the following is a specification.

This invention relates to advertising devices, and it aims to provide improved means whereby the attention of the public may be attracted more effectively than by the ordinary advertising signs, posters, cards or the like at present in general use.

Many advertising signs fail at present to arrest the attention of the public solely because they depict stationary objects, whereas 20 were the objects in a state of movement a considerably greater amount of attraction would result.

According to this invention an object or combination of objects constituting an advertising device is or are adapted to move, either wholly or in part, as the result of sudden shocks transmitted to such device from an external source and without the employment of extraneous mechanical means; said 25 object or objects or portions thereof being attached or not to a stationary or a movable background. The aforesaid shocks may be of a vibratory nature, and may be produced by the movement of a vehicle or vessel 30 wherein or whereon the device is supported, or by the passage of a road or other vehicle or a number of same past a stationary support upon which the device is fixed.

In order to be adapted to vibrate, the object or objects may be mounted upon springs, 40 hinges, pivots or in any other manner whatsoever which will permit of or cause vibratory movement of the object or objects when subjected to shocks of any kind. According 45 to one example, the requisite vibratory movement may be occasioned by an underground railway train in which the device of this invention may be located. Any desired form of pictorial or other advertisement may be thus adapted to receive vibra-

tory movement in imitation of the actual movement or movements of an object or a number of objects, and such movement or movements may be imparted by means other than a railway vehicle. When the invention 55 embodies devices of the type in which a portion or the whole of the device or sign is mounted pivotally and is adapted to move to and fro, it is so constructed that the sign or device shall operate efficiently irrespec- 60 tive of the position in which same may be set or arranged. Accordingly a part or the whole of the sign or device is movable and is pivotally connected to the remainder which is stationary, or to a fixed support, 65 said movable part or whole being weighted and being supported by a member which is free to travel and is provided with a bearing device adapted to roll to and fro upon a stationary portion of the apparatus. Such 70 movement may be imparted by means of the shocks transmitted by any form of vehicle or vessel, when starting or stopping, by any variations in speed or in position of such vehicle or vessel, in or upon or to which such 75 sign or device may be attached, or by means of pressure exerted by the wind. For example a wire, rod, or other suitable form of support is connected pivotally by its upper end to a stationary portion of an advertising sign or device, and to said rod, wire or other support there is attached a movable portion of said advertising sign or device. This movable portion of the sign or device is not suspended from the stationary portion 80 but is supported from below by means of a roller, wheel or the like which is mounted rotatably upon or near the lower extremity of the aforesaid wire, rod or the like, and runs upon a stationary guide track composed of 85 any suitable material and fashioned to the requisite configuration.

The moving elements just referred to may be arranged in a vertical, horizontal or inclined position without prejudice to the operation of the device, and in some cases may be of curved form to accommodate the sign, for example, upon the ceiling of an underground or other railway carriage. In some cases the track may be dispensed with, the 100

bearing roller or wheel making contact directly with the back of a stationary portion of the apparatus.

Manifestly the invention lends itself to 5 multitudinous applications which though differing in design or configuration will all embody the same fundamental principle already hereinbefore set out.

The accompanying drawings illustrate 10 one construction and a modification thereof, which have been selected to exemplify the manner in which the invention may readily be carried into practical effect.

Figure 1 is a rear elevation of a portion 15 of a frame containing an advertising sign constructed in accordance with the invention; and Fig. 2 is a central vertical section of the same. Fig. 3 is a front elevation, drawn to a slightly smaller scale, of the entire frame shown in Fig. 1. Fig. 4 shows in cross section, a slightly modified construction of the mechanism illustrated in the previous figures.

Referring to Figs. 1 to 3 inclusive, *a* is a 25 screen of cardboard or any other suitable material which bears on its face any desirable form of pictorial advertisement, printed or otherwise suitably produced. In the instance illustrated, the representation of 30 an ostrich has been selected. The screen *a* is carried in a suitable wooden or other frame *h* adapted to be secured in any appropriate location, and the head or neck of the ostrich, instead of being reproduced on 35 the screen *a*, are formed by a separate piece *b* of cardboard or the like. In order that the desired movement may be imparted to the sign, the piece *b* is fixed to the end of a spindle *c* which is formed by being bent at right 40 angles from the upper end of a wire or rod *d*, and which passes freely through an aperture formed in the screen *a*. The wire or rod *d* is bifurcated at its lower extremity, and in such bifurcated portion there is 45 mounted a grooved roller *e* adapted to rotate freely upon a spindle *f* and running upon a curved track *g* of sheet metal, wire or other suitable material secured appropriately to the frame *h*. The track *g* therefore 50 entirely supports the weight of the moving parts. When the shocks are transmitted to the sign, as described above, the roller *e* is constrained to travel quickly back and forth along the track *g*, and with said roller move 55 the wire or rod *d*, the spindle *c* and the neck portion *b* of the figure, these parts oscillating as indicated by the dot-and-dash lines in Fig. 3.

In practice, for example, the sudden starting or stopping, or the lateral swaying of a 60 vehicle, (in or on which it is supposed the sign is mounted), will cause the roller *e* to roll to and fro along its guide track *g*, and

hence the neck *b* of the ostrich will also move to and fro, such movement continuing 65 for an appreciable length of time after the transmission of the shocks or vibrations to the sign.

The above described construction is especially suitable for the walls of vehicles 70 or other places, but if the invention is to be applied to the roofs or ceilings thereof, it is preferable to dispense with the curved guide track, and in such a case the construction illustrated in Fig. 4 may with advantage be 75 employed.

In Fig. 4, *j* is a portion of the curved roof or ceiling of a railway carriage, and to it the screen *a* is secured appropriately, so as to leave a space intervening therebetween. 80 As before, the neck portion *b* of the ostrich is secured to spindle *c* bent at right angles to a wire or rod *d*. Instead however of a grooved roller there is loosely mounted at the extremity of the wire or rod *d* a smooth 85 bearing wheel *k* which is supported by the rear face of the screen *a* and which otherwise functions together with the remainder of the device in a manner precisely similar to that already described.

The invention may be applied to any sign whether representing a human being or an animal performing some natural movement, or to a sign illustrating the movement or operation of a piece of mechanism.

What we claim is:—

1. In an advertising device, the combination of a screen provided with an aperture and bearing a portion of a pictorial representation upon its outer face; a member 100 separate from the screen and movable in front thereof across said face, said member bearing the remainder of such representation upon its outer face; and an oscillatory member located behind said screen and having one end thereof laterally bent and projecting loosely through said aperture and the other end provided with a roller, the first-named member being rigidly connected directly to the bent end of said oscillatory 110 member and wholly supported by the same, whereby movement is imparted to said first-named member when sudden shocks are transmitted to the device from an external source.

2. In an advertising device, the combination of a screen having a convex inner face and bearing upon its outer face a portion 120 of a pictorial representation; a member separate from the screen and movable in front thereof across said outer face, said member bearing the remainder of such representation upon its outer face; an oscillatory member located behind said screen and having the first-named member connected directly to it; and a roller secured to said os-

cillatory member and arranged to travel over the said inner face of the screen for wholly supporting said oscillatory member and for imparting movement thereto and 5 to the said first-named member when sudden shocks are transmitted to the device from an external source.

In testimony whereof we have hereunto

set our hands in presence of two subscribing witnesses.

HERBERT G. DE HAMEL.
GEORGE MAKGILL.
